UNITED STATES PATENT OFFICE.

ERNEST S. PECK, OF CLEVELAND, OHIO.

PERCOLATOR.

954,582.

Specification of Letters Patent. Patented Apr. 12, 1910.

Application filed July 22, 1909. Serial No. 509,017.

To all whom it may concern:

Be it known that I, ERNEST S. PECK, a citizen of the United States, and a resident of Cleveland, county of Cuyahoga, and State of Ohio, have invented a new and useful Improvement in Percolators, of which the following is a specification, the principle of the invention being herein explained, and the best mode in which I have contemplated applying that principle, so as to distinguish it from other inventions.

The present invention belongs to the same general class of apparatus as the percolators illustrated in two patents Nos. 925,833 and 925,835, issued to me June 22, 1909. In such percolators, which are designed for the extraction of soluble oils and fats, as from tankage or other analogous material forming one of the products of garbage reduction plants or rendering establishments, or from the various oil bearing seeds, a suitable solvent, generally naphtha, is employed for the purpose of taking up the grease or other oleaginous constituents. In use, such solvent is passed through the material in sufficient quantity to thoroughly extract the grease, after which extraction it becomes necessary to recover the portion of the solvent that has been absorbed by the material, the quantity of the solvent thus absorbed being proportionately quite considerable, and the loss, unless it is thoroughly recovered, being a large item of expense in the carrying on of the operation referred to.

The object of the present invention is the further simplification and improvement of the apparatus illustrated and described in the two patents just referred to, whereby the loss of naphtha, owing to the volatilization of the same by the body of air that remains in the tank when the naphtha is introduced, is avoided, as also the making and breaking of the necessary exterior connections with the tank is facilitated.

To the accomplishment of these and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—Figure 1

represents a central longitudinal cross-section of a percolator embodying my several improvements; Fig. 2 is a transverse sectional view thereof in one operative position; Fig. 3 is a similar sectional view thereof but in a different operative position; Fig. 4 is an end elevation of said percolator as viewed from the left in Fig. 1; and Fig. 5 illustrates a detail in the construction of the percolator.

In general, my improved percolator, as will be observed upon reference to the figures just described, comprises a cylindrical drum A disposed in a substantially horizontal position and rotatably supported upon roller bearings a. To this end it is provided with annular bearing rings a' adapted to rest on such rollers and with a gear at one end wherewith suitable driving means may be connected, as will be readily understood.

For the alternate introduction and discharge of the material to be treated, such drum A is provided in its lateral, or cylindrical surface, with a longitudinally extending series of man-holes a", of which three are shown. These man-holes are adapted to be closed by means of covers a", except when the material is being thus passed therethrough. Disposed longitudinally of the drums, and laterally adjacent to said man-holes, is a pipe B that is connected with the interior of the drum by means of a plurality of short connecting pipes b'. The inner ends of said pipes b' that open into the tank's interior, are protected against the entrance of material, that might otherwise obstruct them, by means of a perforated plate B' extending the entire length of the drum, being spaced from the inner wall thereof so as to afford a place for the liquid to collect. Valves b" in the connecting pipes b' permit the latter to be closed when desired. Two other pipes B" similarly extend longitudinally of the drum, being equidistantly spaced about the surface of the latter from such first named pipe B, and so disposed that when pipe B is on the under side of the drum, they will be located substantially on a level with the body of the material being treated within said drum. As will be presently explained, the drum is not completely filled with such material in operating the percolator, but a percolator having a diameter, for example, of seven feet, will ordinarily be filled only to a height of about

five feet. In such case, the pipes B^2 would lie at the opposite ends of a chord located five feet across from the first pipe. Such pipes, like pipe B, are connected with the 5 drum interior by means of a plurality of short pipes b^3 controlled by valves b^4 and having their inner ends protected, as before, by longitudinally extending perforated plates B^3 spaced from the inner wall of the 10 drum. The two pipes thus designed to be located substantially on a level with the material being treated when the percolator is in use, are connected at one end of the drum as shown in Fig. 4, and a branch extension 15 b^5 from the connecting pipe b^6 is brought to a point adjacent to the corresponding outer end of pipe B. The latter and the extension from the other two pipes are provided with a double flange b^7 , so that connection 20 between such ends and exteriorly supported pipes B^4 , through which solvent is supplied and withdrawn, may be simultaneously effected.

It will be understood, of course, that while 25 pipe B with its corresponding perforated plate B' is located contiguously to the man-holes a^8 through which material is supplied and discharged from the drum, such pipe and plate may be just as well located at a 30 greater or less distance from such man-holes, so far as the operation of the mechanism is concerned. In such event, however, the location of the other two pipes will be correspondingly varied.

Substantially diametrically opposite the longitudinal pipe B (whether the latter lies adjacent to man-hole a^8 or not) is yet another longitudinally disposed pipe C that is connected with the drum's interior by 40 means of transversely disposed pairs of branched pipes c respectively controlled by valves c' , such pipes being connected with T's arranged longitudinally along the pipe. For supplying the steam to longitudinal 45 pipe C, a connection c^2 is provided, said connection being on a line with the axis of the drum and permanently made through a suitable stuffing box c^3 , whence radially extends a valve-controlled branch c^4 to the 50 projecting end of said pipe C.

The operation of the percolator, the structure of which has thus been described, is as follows:—The position of the drum shown in Figs. 1 and 2, is that which it will 55 normally occupy when being filled with tankage, as also while the naphtha absorbed by the material is being driven off in the last stage of the operation. When the drum is thus disposed, the covers closing 60 the man-holes may be removed and the drum filled preferably as has been indicated, about two-thirds full of the tankage. Such man-hole being then closed, the drum is rotated and finally left in a position, substantially a half-turn over; thereupon its

interior is flooded with naphtha through pipe B (now disposed on the under side of the drum) so that such solvent may rise upwardly through the material. Any air intermixed with the material is driven out 70 above the naphtha, and as the level of the latter rises above the level of the material, after percolating through the mass, the major portion of the grease will be in the upper stratum of the naphtha, and will escape 75 through the horizontally disposed overflows provided, in effect, by the two pipes B^2 . After this step is completed, it is usually desirable to reverse the flow of naphtha, so as to more thoroughly extract the grease, 80 and on occasion, the drum is preliminarily rotated one or more times in order to thoroughly intermingle its contents with the naphtha. When finally the tank is stopped in reversed position, then the 85 naphtha is admitted through the erstwhile overflows B^2 , and withdrawn from lowermost B of the three pipes, all that will thus flow off, being finally drained away, and the tankage thus left behind, substantially 90 free of grease. As has been explained, however, there will remain a considerable amount of naphtha in such residual tankage, and the recovery of this is next to be effected. To this end steam is supplied 95 through pipe C and its branched connections, the position of the tank being again changed, so as to dispose such pipe and connections on the under side in order that the steam may have to pass through the mass 100 of tankage before it can escape from the drum. Such escape of the steam, together with the associated naphtha vapors, is by way of a pipe D, supported exteriorly of the drum, and passing through a suitable 105 stuffing box d in the end thereof, opposite to that at which the steam is supplied. A plate d' serves as a shield for the inner end of the pipe, to prevent the entrance therein of the solid material being treated. Outside of the drum, such vapor discharge pipe 110 is connected with a suitable condenser (not shown).

By reason of the unique arrangement of the connections for the three pipes utilized 115 in supplying naphtha to and withdrawing the same from the body of the tankage, such connection may be made or broken with little inconvenience, and this phase of the operation relieved of much of its burden. 120 It will furthermore be observed that whether the naphtha be supplied to the undermost pipe B or to the pipes B^2 on a level with the upper portion of the tankage, such naphtha is at no time passed 125 through the overlying body of air that remains during this part of the operation in the drum. The volatilization of naphtha that otherwise occurs is thus kept at a minimum, and a corresponding saving thereof 130

secured; for such volatilized naphtha once intermingled with the air is practically noncondensable, and so lost.

Other modes of applying the principle of my invention may be employed instead of the one explained, change being made as regards the mechanism herein disclosed, provided the means stated by any of the following claims or the equivalent of such stated 10 means be employed.

I therefore particularly point out and distinctly claim as my invention:—

1. A percolator comprising a suitable receptacle provided with openings for the supply and discharge of the material to be treated; connections to said receptacle for introducing the solvent, said connections lying below the normal level of the material in said receptacle; other connections, substantially on a line with such level, for withdrawing the upper stratum of the solvent when thus introduced; and means for reversing the positions of said connections with relation to said level.

2. A percolator comprising a suitable receptacle provided with openings for the supply and discharge of the material to be treated; connections to the under side of said receptacle for introducing the solvent, whereby the latter may be caused to rise upwardly through the material; other connections, substantially on a level with the material in said receptacle, for withdrawing the upper stratum of the solvent thus introduced; and means for reversing the positions of said connections with relation to said level.

3. A percolator comprising a suitable receptacle provided with openings for the supply and discharge of the material to be treated; connections to the under side of said receptacle for introducing the solvent, whereby the latter may be caused to rise upwardly through the material; a horizontal overflow connected with said receptacle substantially on a level with the material therein for withdrawing the upper stratum of the solvent thus introduced; and means for reversing the positions of said connections and said overflow with relation to said lever.

4. A percolator comprising a rotatable, substantially horizontal drum provided with openings in its cylindrical wall for the supply and discharge of the material to be treated; and circumferentially spaced connections to such wall for introducing and withdrawing solvent, respectively, said connections being so disposed that when the inlet connection is on the under side the discharge connection is located substantially on a level with the material in said receptacle, the connections for introducing and withdrawing solvent being unconnected with each other.

5. A percolator comprising a rotatable, substantially horizontal drum provided with openings in its cylindrical wall for the sup-

ply and discharge of the material to be treated; and a plurality of series of longitudinally ranged connections to such wall for introducing and withdrawing solvent, respectively, said series being circumferentially spaced about said drum and so disposed that when the inlet connection is on the under side a discharge connection is located substantially on a level with the material in said receptacle, the connections for introducing and withdrawing solvent being unconnected with each other.

6. A percolator comprising a rotatable, substantially horizontal drum provided with openings in its cylindrical wall for the supply and discharge of the material to be treated; and three series of longitudinally ranged connections to such wall for introducing and withdrawing solvent, respectively, two of said series being equidistantly spaced about the circumference of said drum from the third and so disposed that when the inlet series is on the under side, the discharge series are located substantially on a level with the material in said receptacle, the connections for introducing and withdrawing solvent being unconnected with each other.

7. A percolator comprising a rotatable, substantially horizontal drum provided with a series of longitudinally aligned man-holes in its cylindrical wall for the supply and discharge of the material to be treated; and a plurality of series of longitudinally ranged connections to such wall for introducing and withdrawing solvent, respectively, one of said series being located contiguously to said man-holes and another being circumferentially spaced therefrom so that the discharge connection is located substantially on a level with the material in said drum when the inlet connection is on the under side thereof, the connections for introducing and withdrawing solvent being unconnected with each other.

8. A percolator comprising a rotatable, substantially horizontal drum provided with a series of longitudinally aligned man-holes in its cylindrical wall for the supply and discharge of the material to be treated; and three series of longitudinally ranged connections to such wall for introducing and withdrawing solvent, respectively, one of said series being located contiguously to said man-holes and the other two being equidistantly spaced about the circumference of said drum therefrom and so disposed that when such first series is on the underside, such two are located substantially on a level with the material in said receptacle, the connections for introducing and withdrawing solvent being unconnected with each other.

9. A percolator, comprising a rotatable, substantially horizontal drum provided with a series of horizontal man-holes in its cylindrical wall for the supply and discharge

of the material to be treated; three series of longitudinally ranged connections to such wall for introducing and withdrawing solvent respectively, one of said series being located contiguously to said man-holes, and the other two being equidistantly spaced about the circumference of such drum therefrom and so disposed that when such first series is on the under side, such two are located substantially on a level with the material in said receptacle.

10. A percolator comprising a rotatable, substantially horizontal drum provided with a series of longitudinally alined man-holes in its cylindrical wall for the supply and discharge of the material to be treated; a plurality of series of longitudinally ranged connections to such wall for introducing and withdrawing solvent, respectively, one of said series being located contiguously to said man-holes and another being circumferentially spaced therefrom so as to be located substantially on a level with the material in said drum when said first series is on the under side thereof; and connections to the portion of such wall substantially diametrically opposite from said man-holes for introducing steam.

11. A percolator comprising a rotatable, substantially horizontal drum provided with a series of longitudinally alined man-holes in its cylindrical wall for the supply and discharge of the material to be treated; three series of longitudinally ranged connections to such wall for introducing and withdrawing solvent, respectively, one of said series being located contiguously to said man-holes and the other two being equidistantly spaced about the circumference of said drum therefrom and so disposed that when such first

series is on the under side, such two are located substantially on a level with the material in said receptacle; and connections to the portion of such wall substantially diametrically opposite from said man-holes for introducing steam.

12. A percolator comprising a rotatable, substantially horizontal drum provided with openings in its cylindrical wall for the supply and discharge of the material to be treated; three pipes disposed longitudinally of said drum, two of said pipes being equidistantly spaced about the circumference of said drum from the third; and a series of connections between each of said pipes and the drum-interior, the ends of said pipes being brought to a common point, whereby exterior connection may be made with all simultaneously, substantially as described.

13. A percolator comprising a rotatable, substantially horizontal drum provided with a series of longitudinally alined man-holes for the supply and discharge of the material to be treated; three pipes disposed longitudinally of said drum, one of said pipes being located contiguously to said man-holes and the other two being equidistantly spaced therefrom about the circumference of said drum; a series of connections between each of said pipes and the interior of the drum; and an exterior connection for said pipes having a double opening, one for said first named pipe and a common opening for the other two, substantially as described.

Signed by me this 20th day of July, 1909. 75
